Primary Examiner — Jae Liang*Assistant Examiner* — Christopher Torma(57) **CLAIM**

The ornamental design for a foldable cabinet, as shown and described.

DESCRIPTION

FIG. 1 is a front, top and right-side perspective view of a foldable cabinet showing my new design;
FIG. 2 is a front elevation view thereof;
FIG. 3 is a rear elevation view thereof;
FIG. 4 is a left side elevation view thereof;
FIG. 5 is a right side elevation view thereof;
FIG. 6 is an enlarged top plan view thereof;
FIG. 7 is an enlarged bottom plan view thereof;
FIG. 8 is a rear, top and left-side perspective view thereof;
and,
FIG. 9 is an alternate configuration in another perspective view thereof.

The broken lines throughout the drawing figures depict portions of the foldable cabinet that form no part of the claimed design.
